UNITED STATES PATENT OFFICE.

EDMOND VERSTRAETE, OF NUTLEY, NEW JERSEY.

THERMOSTATIC FURNACE-DAMPER CONTROL.

Application filed July 1, 1927. Serial No. 202,794.

This invention relates to automatic damper control mechanism for heating furnaces; and this application is a continuation in part of an application for United States Letters Patent filed by me on or about May 29, 1925, and identified by Serial Number 33,656.

This invention has for its principal object to provide a novel and simply constructed thermostatically controlled electro-mechanical means for automatically actuating the draft dampers of heating furnaces whereby the temperature in artificially heated buildings may be in turn automatically regulated.

Other objects of this invention, not at this time more particularly enumerated, will be clearly understood from the following detailed description of the same.

The invention is clearly illustrated in the accompanying drawings, in which:—

20 Figure 1 is a diagrammatic view illustrating the operation of the apparatus when functioning to open the drafts of a heating furnace; and Figure 2 is a similar view illustrating the operation of the apparatus 25 when functioning to close the drafts of the heating apparatus.

Figure 3 is a side view in elevation of the electro-mechanical furnace draft actuating means, with the casing thereof open to display the interior mechanism thereof; Figure 4 is a vertical sectional view of the same, taken on line 4—4 in Figure 3; and Figure 5 is a fragmentary detail view of an electric circuit control switch which forms a novel and essential part of the electro-mechanical furnace draft actuating means.

Similar characters of reference are employed in all of the hereinabove described views, to indicate corresponding parts.

40 Referring now to said drawings, the reference character 6 indicates a casing in which the electro-mechanical furnace draft actuating mechanism is enclosed, and which may be suitably mounted or supported in the vicinity 45 of the furnace to be served thereby. The front wall 7 of the casing 6 may be made in the form of a removable part or cover-plate. The rear wall 8 of the casing 6 and said front wall or cover plate 7 thereof are respectively 50 provided with bearing portions 9 and 10 in alignment one with the other. Journalized in and extending through and between said bearing portions 9 and 10 is a driven shaft 11.

Fixed on the exteriorly projecting forward end of said shaft 11 is a crank-arm 12; and, 55 in like manner, fixed on the exteriorly projecting rearward end of said shaft 11 is a second crank-arm 13. Said crank-arms 12 and 13 extend in opposite directions, so that when one is up the other is down and vice versa. 60

Secured within and to the top wall 14 of the casing 6 is an electric motor 15, which when served with electric current is adapted to drive the shaft 11 through suitable intermediate transmission mechanism. Such transmission mechanism preferably comprises a drive-pinion 16 fixed on the armature shaft 16' of said motor 15, which pinion 16 meshes with and drives a gear 17 fixed on a transmission shaft 18. The side walls of said casing 6 are respectively provided with bearing members 19 and 20 in transverse alignment one with the other. Said transmission shaft 18 is journaled in and extends between said bearing members 19 and 20. Secured 75 upon said transmission shaft 18 is a drive worm 21 which meshes with and drives a worm gear 22 which is fixed on said main shaft 11 and whereby the latter is rotated.

Supported by posts 23 extending forwardly into the casing interior from the rear wall 8 thereof, is a carrier bar or plate 24 of insulation material upon which is supported a mechanically actuated electric switch mechanism for inclusion in the thermostatic control circuit of the apparatus. Fixed on said carrier bar or plate 24 intermediate its ends is a metallic circuit connection 25 provided with a binding screw 26 or other suitable means for connecting a circuit wire therewith. The lower end of said circuit connection 25 is furnished with a fulcrum pin 27 upon which is pivotally mounted an oscillatable switch member having oppositely extending switch arms 28 and 29. Secured on said carrier bar or plate 24, adjacent to one end thereof, is a contact clip 30 engageable at proper times by the switch arm 28 of said oscillatable switch member, said contact clip 30 being provided with a binding screw 31 or other suitable means for connecting a circuit wire therewith; and, in like manner, secured on said carrier bar or plate 24, adjacent to its opposite end, is a contact clip 32 engageable at proper times by the switch arm 29 of said oscillatable switch member, said

contact clip 32 being likewise provided with a binding screw 33 or other suitable means for connecting a circuit wire therewith.

- A suitably insulated terminal binding post 34 is provided in connection with the casing wall in desired location to receive connection at its exterior end of an electrical conductor 35 leading from any suitable source of electric energy. One pole of the motor 15 5 is connected with the interior end of said binding post 34 by an electrical conductor 36. The other pole of said motor is connected with the inner end of a similar terminal binding post 34' by an electrical conductor 36', and from the outer end of said binding post 34' leads the return circuit wire 37. Included in the motor circuit thus provided is a normally open switch forming part of a relay mechanism to be presently described.
- 20 Another suitably insulated binding post 34" is provided in connection with the casing wall in desired location to receive connection at its exterior end of a shunt branch conductor 35' leading from the current delivery side of said motor circuit. Included in said branch conductor 35' is a voltage reducing coil or resistance R, or, if desired a transformer or other suitable electrical means for stepping down the voltage in a thermostatic control circuit in shunt with said motor circuit and operating, as will be presently made clear, to open and close the latter at proper times. The inner end of said binding post 34" is connected with said circuit connection 25 of said mechanically actuated switch mechanism by an electrical conductor 25'. A pair of suitably insulated terminal binding posts 38 and 39 are also provided in connection with the casing wall in 25 desired location; the contact clip 30 being connected with the interior end of the binding post 38 by an electrical conductor 40, while the contact clip 32 is connected with the interior end of the other binding post 39 by an electrical conductor 41. A thermostatic switch means is suitably located so as to be subject to temperature variations within the building heated by the furnace served by the electro-mechanical draft actuating mechanism. Said thermostatic primary switch means may be of any desired specific form and construction comprising a thermostatic switch arm 42 subject to deflection under temperature variations, and a 50 pair of fixed contacts 43 and 44 selectively engageable by said thermostatic switch arm 42. One fixed contact, as 43, is connected in circuit with said contact clip 30 by an electrical conductor 45 leading thereto from the binding post 38; and the other fixed contact, as 44, is connected in circuit with said contact clip 32 by an electrical conductor 46 leading thereto from the binding post 39. The thermostatic switch arm is connected by a 55 circuit wire or conductor 47 with one pole

of a magnet M forming part of the relay controlling the opening and closing of the main motor circuit, the other pole of said magnet M being connected to the return wire 37 of said motor circuit.

70 Cooperating with said magnet M as its armature is a pivoted switch arm A, normally retained in open position by a spring S. The return wire 37 of the motor circuit is connected with said switch arm A, and the continuation of said return wire 37 is connected with a stationary contact C with which said switch arm A is engaged when moved by the energizing of the magnet M, thus closing the main circuit serving the motor 15.

75 The reference character 48 indicates an oscillatable trip-lever which is pivoted by its lower end on a fulcrum stud or screw 49 fixed in a boss 50 within the lower end of said casing 6. Said trip-lever 48 is provided intermediate its ends with a yoke-frame 51 which straddles said main shaft 11, and fixed on the latter so as to be rotated thereby is a cam-member 52. Said cam-member 52, when rotated, engages the sides of said yoke-frame 51 and causes said trip-lever 48 to swing or oscillate on its fulcrum. The free end of said trip-lever 48 is provided with a socket-member 53 in which is housed a compression or thrust spring 54 which yieldably thrusts 80 against the inner end of a nose-piece 55 which projects outwardly from said socket-member 53 and is slidable therein. Said nose-piece 55 is provided in its body with an elongated slot 56 through which extends a stop-pin 57 fixed crosswise within said socket-member 53, thus serving to limit the outward movement of said nose-piece whereby the same is retained in operative assembled relation to said socket-member 53.

85 The reference character 58 indicates a heating furnace to be served by the draft actuating mechanism. Said furnace is provided with any suitable form of ash-pit or bottom air admission damper means 59 pivoted for 90 opening and closing movement, and with a pivoted smoke-pipe damper means 60 of any suitable form. The crank-arm 12 of the damper actuating mechanism is connected with said bottom damper 59 through a suitable connection such as a flexible wire, cord, chain or the like 61, which may be guided for operative movement by suitably located pulley or pulleys 62; and in like manner the crank-arm 13 of the damper actuating mechanism is connected with said smoke-pipe damper 60 through a suitable connection such as a flexible wire, cord, chain or the like 63, which also may be guided for operative movement by suitably located pulley or 95 pulleys 64.

100 In the operation of the damper actuating mechanism, the thermostatic control circuit of the apparatus governs the properly timed opening and closing of the motor service cir-

cuit, the mechanically actuated switch mechanism serving to break the thermostatic control circuit after a given actuation of the furnace dampers to thereby in turn cause the interruption of the motor circuit through the release of the relay switch, and at the same time alternately bringing into the control circuit the respective fixed contacts of the thermostatic switch means. By the arrangement 5 of main motor service circuit, and shunt thermostatic control circuit including a voltage reducing means, the device may be easily connected with 110 or 220 volt power lines, where by adequate current for motor operation is 10 assured, while a reduced or low voltage current is supplied through the thermostatic switch to protect its delicate contacts against injury. This electrical mode of connection is not per se new with me, the new feature 15 of my arrangement being the provision of the novel mechanically actuated switch mechanism in the thermostatic control circuit, the construction and arrangement of which is such that not only a very quick break is 20 attained, but the relation of this switch mechanism to the damper actuating elements is such that accurate control and operation of the latter is secured without risk of either overthrow or partially completed movements of the same. 25

Assume that the thermostatic switch arm 42 deflects to the left to engage the contact 44 under falling room temperature conditions, and deflects to the right to engage the contact 35 43 under rising room temperature conditions. When the parts of the electro-mechanical damper actuating mechanism are disposed in the position shown in Figure 3 the air admission damper 59 is open and the smoke-pipe 40 damper is closed, under these circumstances the switch arm 28 being engaged with the contact clip 30 so that the thermostat contact 43 is operatively connected in the thermostatic control circuit. Under these conditions the 45 furnace is active. As the heat provided by the furnace operation causes room temperature to rise, the effect of said rising temperature is to deflect the thermostatic switch arm 42 toward the contact 43, and when the engagement of the latter by the former occurs 50 the motor circuit will be completed. The electric current being then delivered by the conductors 35 and 35', through the resistance R, conductor 25', circuit connection 25, mechanical switch arm 28, contact clip 30, thermostatic contact 43, thermostatic switch arm 42, conductor 47, to the magnet M and thence back to the source of energy through the conductor 37. The thermostatic control switch 55 being thus closed the magnet M is energized and pulls toward it the switch arm A so as to bring the same into engagement with the contact C. In this manner the service circuit through the motor is closed and the motor is 60 caused to operate. The operation of the motor drives the shaft 11 through the intermediate transmission mechanism. The rotation of said shaft 11 turns the crank-arm 12 down and the crank-arm 13 up, thereby relaxing the connection 61 to permit the damper 59 to 65 close, and drawing up the connection 63 to open the damper 60, whereby the furnace is checked. As the shaft 11 rotates to operate the crank-arms 12 and 13 in the manner and for the purposes above described, the cam-member 52 is also rotated in engagement with the yoke-frame 51 whereby the trip-lever 48 is caused to swing from right to left. In thus moving, the trip-lever carries the nose-piece 55 away from the upwardly swung switch-arm 28 and causes the same to pass the pivotal point of the mechanically actuated switch means and thence into engagement with the downwardly swung switch arm 29, the nose-piece yielding inwardly against the compression of the spring 54 during such movement, so that upon passing into engagement with said downwardly swung switch arm the outward thrust of the spring presses the nose-piece sharply upward, and thus 70 swings upward the switch-arm 29 into engagement with the contact clip 32, while at the same time swinging downward the switch-arm 28 out of engagement with the contact clip 30 with a quick circuit breaking 75 movement. The thermostatic control circuit is thus immediately interrupted whereby the magnet M is deenergized and in turn the motor service circuit is interrupted by the movement of the switch arm A away from the contacts C under the influence of the spring S. It will be obvious that the interruption of current to the motor stops the power transmission to the shaft 11, the arrangement of the means for actuating the mechanical switch being such that rotation of the shaft 11 is effectively stopped upon completion of a 80 half revolution thereof, such half revolution being sufficient to turn the crank-arms 12 and 13 in the manner and for the purposes above stated. The operations of the mechanically actuated switch, as thus brought about, further serves to alter the thermostatic control circuit, so that as the thermostat contact 43 is cut out of such circuit the opposite thermostat contact 44 is brought into the circuit by the engagement of the switch-arm 29 with the contact clip 32, thus automatically preparing the thermostatic switch for operation under falling temperature conditions. When, therefore, under checked condition of the furnace, room temperature falls to that degree sufficient to deflect the thermostatic switch-arm 42 to the left and into engagement with the thermostat contact 44, the motor circuit 85 will again be closed through the operation of the relay switch, and the motor 15 put in motion, power being thereupon again transmitted to the shaft 11, whereby the crank-arm 12 will be turned up and the crank-arm 13 drawn 90

down to open the damper 59, and to relax the connection 63 to close the damper 60, so that normal combustion of fuel within the furnace with consequent delivery of heat is resumed. Upon completion of the half turn of the shaft 11 whereby consummation of this operation is attained, the cam 52 during its rotation will again actuate the trip-lever 48 to move the nose-piece 55 out of engagement 10 with the switch-arm 29 and into engagement with the switch-arm 28, thus oscillating the mechanically operated switch to break the thermostatic control circuit at the contact clip 32 while at the same time resetting such 15 circuit through contact clip 30 to bring the thermostat contact 43 again into active control circuit relation ready to close the same when the thermostatic switch-arm 42 is moved into engagement therewith under rising 20 temperature conditions. It will be evident that the thermostatic switch may be of the kind that can be set or regulated to make circuit closing contact at desired predetermined maximum and minimum room 25 temperatures.

While I have herein shown and described my novel electro-mechanical damper actuating means in one preferred form and by way of example, it will be obvious that many 30 changes, modifications and adaptations may be made therein and in its mode of application to a furnace which will nevertheless be comprised within the spirit of my invention; consequently I do not limit myself to the exact 35 arrangements and combinations of parts hereinabove described, nor do I confine myself to the exact details of the construction of said parts as shown in the accompanying drawings.

Having thus described my invention, I claim:—

1. An electro-mechanical damper actuating mechanism, comprising a shaft provided with damper actuating means; an electric motor 45 for driving said shaft; a circuit for said motor including a relay actuated switch; a thermostatic control circuit for operating said relay actuated switch, comprising a thermostatic switch arm and a pair of fixed thermostatic contacts selectively engageable by said arm when influenced by rising and falling temperature, a control circuit interrupter comprising an oscillatable switch means and a pair of stationary contacts selectively engageable thereby, said stationary contacts of said interrupter being respectively connected in series with the respective fixed thermostat contacts; a pivoted trip lever having a yieldable nosing to engage and operate said oscillatable switch means of said interrupter; and said shaft having a cam for actuating said

trip-lever upon completion of a damper actuating operation.

2. An electro-mechanical damper actuating mechanism, comprising a shaft provided with 55 damper actuating means; an electric motor for driving said shaft; a circuit for said motor including a relay actuated switch; a thermostatic control circuit for operating said relay actuated switch, comprising a thermostat 70 having a pair of spaced apart fixed contacts and a thermostatic switch arm intermediate said fixed contacts, a cut-out switch having a pair of spaced apart contact clips, an oscillatory switch member having oppositely extending arms pivoted intermediate said contact clips and so arranged that when one arm is in contact with one contact clip the other arm is out of contact with the other contact clip, means for electrically connecting together 75 contact clips of said cut-out switch with corresponding fixed contacts of said thermostat; a pivoted trip lever having a yieldable spring 80 pressed nosing to engage and operate said oscillatory switch member; and means driven by said shaft for operating said trip lever upon completion of a damper actuating operation to thereby interrupt the control circuit 85 closed through one interconnected contact clip and fixed thermostat contact and at the same time set said control circuit for closing 90 through the other interconnected contact clip and fixed thermostat contact.

3. An electro-mechanical damper actuating mechanism, comprising a shaft provided 95 with damper actuating means; an electric motor for driving said shaft; a circuit for said motor including a relay actuated switch, a thermostatic control circuit for operating said relay actuated switch, comprising a thermostat 100 having a pair of spaced apart fixed contacts and a thermostatic switch arm intermediate said fixed contacts, a cut-out switch having a pair of spaced apart contact clips, an oscillatory switch member having oppositely 105 extending arms pivoted intermediate said contact clips and so arranged that when one arm is in contact with one contact clip the other arm is out of contact with the other contact clip, means for electrically connecting together 110 contact clips of said cut-out switch with corresponding fixed contacts of said thermostat; a pivoted trip lever having a yieldable spring 115 pressed nosing to engage and operate said oscillatory switch member; a yoke-frame connected with said trip-lever; and a cam on said shaft cooperating with said yoke-frame to actuate said trip-lever.

In testimony, that I claim the invention set forth above I have hereunto set my hand this 120 27 day of June, 1927.

EDMOND VERSTRAETE.
